United States Patent Office.

SAMUEL MALES, OF CINCINNATI, OHIO.

Letters Patent No. 73,907, dated January 28, 1868.

IMPROVEMENT IN URINALS.

The Schedule referred to in these Letters Patent and making part of the same.

TO WHOM IT MAY CONCERN:

Be it known that I, SAMUEL MALES, of Cincinnati, Hamilton county, Ohio, have invented a new and useful Urinal; and I hereby declare the following to be a full, clear, and exact description thereof, reference being had to the accompanying drawings, making part of this specification.

The object of this invention is to provide what is known to be one of the greatest wants of the city public at the present time, viz, a public necessary-urinal, difficult to commit any nuisance in, and which cannot be made a lurking-place for evil-disposed persons. In the accompanying drawings—

Figure 1 is a perspective view of a urinal of my invention.

Figure 2 is a vertical section of the same.

Figure 3 shows a modification for the use of females.

Figure 4 is a horizontal section of a form used for an open space, such as a market or public landing.

Figure 5 is a modification, in horizontal section, in which the doors are hinged to the house-wall.

Figure 6 is a vertical section, showing a further modification.

Figure 7 is a horizontal section through the guard or shield.

Figures 8 and 9 show modifications of my curved partitions.

A is a house or other wall; B, a frame erected thereto. C is a plate let into and attached to the wall, having a receptacle, D', and pipe E, to catch and conduct the urine to the catch-basin or sewer. F F' are doors hinged at f, having a spring, G, tending to keep them closed. The door F has a catch, H, which engages over the edge of the door F', when the necessary is occupied, as seen in dotted red lines in fig. 1.

In the modification intended for females, (see fig. 3,) the doors will nearly reach the ground; while in those intended for men, (see figs. 1, 2, 4, and 6,) the doors will not reach within twelve or fourteen inches of the ground, so that the commission of a nuisance upon the ground will be impossible without an exposure of the person, and no one can lurk inside for any criminal purpose without being seen.

It will be seen that the doors are folded past each other when the necessary is unoccupied, and in this case, that there is not room for any evil-disposed person to conceal himself behind them, as they approach so near to the back part of the urinal, thus obviating one great objection to the introduction of public necessities in cities, namely, the forming of a lurking-place for thieves. My necessary has a "seat," d, so formed as that no one can stand upon the same, but must use it in a proper manner.

The main claim as to utility, made, next to avoidance of the objectionable features of such structures heretofore, namely, as hiding-places for evil-disposed persons, and as places particularly subject to the commission of nuisances, is that so very little room is taken up. Where permissible, economy of space may be still further secured, as in fig. 5, by hinging the doors upon the wall, and making a slight recess, a, of eight to twelve inches, at its greatest depth into the wall, so that the projection of the doors need not exceed six inches from the general face of the wall. In this case the hinge is affixed to an iron block, I, let into the wall for that purpose. Where an attachment to the house or other wall would be objectionable, I provide a separate frame, complete in itself, as seen in fig. 6, in which J is the supporting-frame and K a plate, forming a guard or shield, shown by horizontal section in fig. 7, having a conducting-pipe, E, leading from the pan D, and formed with such concavity as to conduct to the sink M the misdirected urine of inebriate and careless persons. This whole structure need not project more than two and a half inches from the wall. The frame J may be secured to a foot, J', of stone or metal.

Fig. 4. shows a modification intended for open spaces. It takes double form, and the "seats" can be so arranged in respect to each other that by adopting a curved form for the partition L between the two sides, thereby forming a recess for each seat, the width of the house, in its closed or unoccupied condition, need not exceed twenty inches.

I do not confine myself to the use of two doors, F F', as substantially the same end could be accomplished by use of three, or even more.

My urinal is applicable to private residences as well as to public use.

One obvious advantage of my arrangement is that the position of the doors indicates to outsiders whether the urinal be occupied or not, and the space enclosed by the doors F F', when fastened in condition for use, is

most roomy in front of the basin, affording an additional guarantee against misuse of the necessary or urinal. Although springs are here described for closing the doors, it is obvious that weights or gravitating hinges may be used for this purpose.

I claim herein as new, and of my invention—

A urinal or necessary, having two or more doors, F F', so constructed as to stay each other in the partially-open position, and to close automatically when liberated, substantially as and for the purposes set forth.

In testimony of which invention, I hereunto set my hand.

SAMUEL MALES.
